United States Patent Office.

M. W. MARSHALL, OF HUDSON, MICHIGAN.

Letters Patent No. 91,460, dated June 15, 1869.

IMPROVEMENT IN SKATES.

The Schedule referred to in these Letters Patent and making part of the same.

To all whom it may concern:

Be it known that I, M. W. MARSHALL, of Hudson, in the county of Lenawee, and in the State of Michigan, have invented certain new and useful Improvements in Skates; and do hereby declare that the following is a full, clear, and exact description thereof, reference being had to the accompanying drawings, and to the letters of reference marked thereon.

The nature of my invention consists in so constructing a skate, that by turning a screw-shaft, under the foot-plate of the same, a strap across the foot will be tightened, and, at the same time, the heel secured in a clamp.

In order to enable others skilled in the art to which my invention appertains, to make and use the same, I will now proceed to describe its construction and operation, referring to the annexed drawings, and in which—

Figure 1 is a side view of my skate.

Figure 2 is a plan view of the same.

Letter A represents the foot-plate, which rests upon the two standards, e, and which can be made of either wood or iron.

Towards the rear end of this plate there is a long slot cut, in which the clamp B moves forward and back, while upon the same end there is placed a projection, sharpened on its inner side, against which the heel bears.

Upon the under side, towards the front, there are two or more buttons attached, upon which the end of the strap C is fastened.

Passing through the two standards, e, is the shaft D, which has two slots cut through its front end, one on each side of the standard, through which the strap is passed, so that when the shaft is turned, the strap will wrap around it, so as to tighten over the foot.

In front of the rear standard this shaft is cut like a screw, so as to operate the heel-clamp B.

The end of this shaft is formed into a thumb-screw, so that the shaft can be turned without the use of a key, and is ready for use at all times.

Just in the rear of the standard there is a ratchet cut or placed, in which the dog E catches, so as to hold the shaft, after it has once been turned, so as to fasten the skate to the foot.

Working upon the shaft, and in the slot in the foot-plate, is the heel-clamp B.

The edge of this clamp towards the heel is cut like a saw, so that it will securely hold the heel after once catching it.

In turning the shaft, this clamp is not only operated, but the strap tightened or loosened at the same time.

Having thus described my invention,

What I claim, and desire to secure by Letters Patent, is—

1. The shaft D, which has one or more slots in its end, a screw-thread and ratchet upon its surface, and one end so formed as to be used as a thumb-screw, substantially in the manner and for the purpose specified.

2. The screw-shaft D and strap C, constructed and arranged as described, for the purpose of fastening the skate to the foot, substantially as herein set forth.

3. In combination with the screw-shaft D and strap C, the clamp B, working on the same shaft, substantially as and for the purposes herein set forth.

In testimony that I claim the foregoing, I have hereunto set my hand, this 10th day of April, 1869.

Witnesses: M. W. MARSHALL,

PERRY SHUMWAY,

ALBERT CARPENTER.
